DESIGN FOR AN EXTERNAL ENERGIZER FOR INTERNAL COMBUSTION ENGINE STARTERS

David J. Conant, Cleveland Heights, Ohio, assignor to Jack & Heintz, Inc., Bedford, Ohio, a corporation of Ohio

Application September 19, 1942, Serial No. 108,280

Term of patent 14 years

To all whom it may concern:

Be it known that I, David J. Conant, a citizen of the United States, residing at Cleveland Heights, in the county of Cuyahoga and State of Ohio, have invented a new, original, and ornamental Design for an External Energizer for Internal Combustion Engine Starters, of which the following is a specification, reference being had to the accompanying drawing, forming part thereof, wherein:

Figure 1 is a side elevational view of an external energizer for internal combustion engine starters showing my new design;

Figure 2 is a side elevational view taken at right angles to Figure 1;

Figure 3 is an end view taken from the drive shaft end of the energizer; and

Figure 4 is an end view taken from the handle end.

I claim:

The ornamental design for an external energizer for internal combustion engine starters, substantially as shown.

DAVID J. CONANT.
